UNITED STATES PATENT OFFICE.

OSCAR W. FAUSER, OF BELLEROSE, NEW YORK.

DESIGN FOR RUG OR SIMILAR ARTICLE.

Application filed November 21, 1928. Serial No. 28,970. Term of patent 7 years.

To all whom it may concern:

Be it known that I, OSCAR W. FAUSER, a citizen of the United States of America, residing at Bellerose, in the county of Nassau and State of New York, have invented a certain new, original, and ornamental Design for Rug or Similar Article (Case #6), of which the following is a specification, reference being had to the accompanying drawing, forming a part hereof.

The figure is a plan view of a portion of a rug or similar article showing my design, it being understood that the design in the representative illustration is repeated throughout the extent of the rug.

I claim:

The ornamental design for rug or similar article substantially as shown and described.

In testimony whereof, I affix my signature.

OSCAR W. FAUSER.
